CLAIM

The ornamental design for a carton, as shown and described.

DESCRIPTION

FIG. 1 is a perspective view of a carton;

FIG. 2 is a front view of the carton of FIG. 1;

FIG. 3 is a side view of the carton of FIG. 1;

FIG. 4 is a rear view of the carton of FIG. 1, opposite the front view of FIG. 2;

FIG. 5 is a side view of the carton of FIG. 1, opposite the side view of FIG. 3;

FIG. 6 is a top view of the carton of FIG. 1; and,

FIG. 7 is a bottom view of the carton of FIG. 1; opposite the top view of FIG. 6.

The broken lines illustrate portions of the carton and form no part of the claimed design.

1 Claim, 4 Drawing Sheets
